PHYSIOTHERAPEUTIC DEVICE

Perry M. Thomas, Elgin, Ill.

Application November 2, 1935, Serial No. 47,951

9 Claims. (Cl. 128—184)

This invention relates to physio-therapeutic devices of the kind particularly adapted for administration of gases such as oxygen, carbon dioxide and the like for the treatment of diseases, infections and the like.

It is often desirable to introduce oxygen or other gas into the blood stream as in the treatment of persons suffering from pneumonia. Heretofore it has been the custom to place the 10 person in an enclosure, commonly referred to as an oxygen tent, and to regulate the atmosphere in the enclosure so that it will be high in oxygen. This is expensive particularly because of the relatively large quantity of gas that need be used 15 and, in many instances, due to the congested condition of the respiratory organs it has been found that insufficient oxygen reaches the lungs. It is the primary object of this invention to overcome these and kindred objections and difficulties and to facilitate the administration of 20 oxygen or other gases.

Another important object is to enable the administration of a measured quantity of oxygen or other gas so that it may be administered 25 desired or required and thereby enable close control of the treatment and reduce the entailed expense by avoiding unnecessary losses of gas.

Further objects are to withdraw gas from a high pressure source and to reduce the pressure 30 thereof so as to enable proper administration; to indicate directly the quantity of gas available for administration; and to indicate and control the administration pressure so that the gas may be properly administered.

Still further objects are to provide a novel 35 compact device of simple and economical construction which may be easily transported and employed in the administration of gases; to afford a compact source of gas which may be easily 40 transported with the device; and to enable subcutaneous, rectal or other administration of gas.

A selected embodiment of the invention is 45 illustrated in the accompanying drawing wherein—

Fig. 1 is a front elevation;

Fig. 2 is a side elevation;

Fig. 3 is a rear elevation in which certain parts are broken away;

Fig. 4 is a top plan; and

Fig. 5 is a sectional detail view of a valve 50 used in the device and taken substantially on the line 5—5 on Fig. 2.

The embodiment of my invention illustrated 55 in the accompanying drawing includes a front panel P and a base B that are adapted to be

mounted in a suitable casing C to facilitate transportation thereof, and the various instrumentalities included in my device are mounted on the panel P and base B whereby a self-contained portable device is provided.

A block 6 is mounted on the base B along one side of the panel P and is suitably joined to both the base and the panel. A plurality of sockets S is provided in the block, each of which opens through the panel but is closed at its rear end and serves as a receptacle in which gas containing cylinders 7 may be stored so that an adequate supply of gas may be transported with the device. The cylinders 7 are small easily handled containers in which gas at high pressure may be stored and are provided with threaded bosses 8 in each of which there is a valve stem 9 of a suitable valve regulating flow to and from the cylinders 7.

A tubular body 10 is mounted in an opening 20 which extends transversely across the block 6 and has a plate 11 at one end thereof secured in a countersunk recess in the outer side face of the block 6. A bore 12 extends longitudinally through the body 10 and is enlarged and tapped as indicated at 13 at its outer end so that the boss 8 of a cylinder 7 may be screwed thereinto. A hollow stud 14 extends into the tapped part 13 of the bore 12 and is projectable into the boss 8 25 to engage the valve stem 9 when the gasket 15 seats at the free end of the boss 8. A hollow stud 14 extends into the tapped part 13 of the bore 12 and is projectable into the boss 8 to engage the valve stem 9 when the gasket 15 30 seats at the free end of the boss 8. A hollow stud 14 extends into the tapped part 13 of the bore 12 and is projectable into the boss 8 to engage the valve stem 9 when the gasket 15 35 seats at the free end of the boss 8. A hollow stud 14 extends into the tapped part 13 of the bore 12 and is projectable into the boss 8 to engage the valve stem 9 when the gasket 15 40 seats at the free end of the boss 8. A hollow stud 14 extends into the tapped part 13 of the bore 12 and is projectable into the boss 8 to engage the valve stem 9 when the gasket 15 45 seats at the free end of the boss 8.

A check valve 17 is provided in the bore 12 and is unseated by the pressure of gas flowing into the bore. Gas flows past this unseated valve to a fitting 18 mounted in the enlarged inner end of said bore. A tube 19 interconnects the coil 20 with the fitting 18, said coil 20 serving as a storage and compensating chamber, as will be explained more fully hereinafter. A pressure gauge 21 is mounted in the panel P and a tube 22 interconnects this gauge with the coil 20.

A pressure reducing valve 23 includes a base 24 that extends through the coil 20 and rests upon the base B and it is fastened to said base by a screw 25 or the like. This pressure reducing valve may be of the kind shown in the patents to Bastian, 1,217,901, patented March 6, 1917 or 1,394,395, patented October 18, 1921, although any suitable pressure reducing valve may be employed. The valve 23 includes a high pressure 55

inlet 26 and a tube 27 interconnects this inlet with the coil 20.

The pressure reducing valve also includes a low pressure outlet 28 in which a valve 29 is fast. The valve body 29 has a tapered bore 30 therein in which a tapered valve member 31 is retained by a cap nut 32 through which the stem 33 of the valve 31 projects. The cap nut 32 is disposed in an opening 34 in the panel P. The stem 33 extends beyond the panel and has a handle 35 mounted thereon. Suitable indicia, such as the word "Off" and an arrow with which the word "Increase" is associated, is provided on the panel P and the handle 35 is so connected to the stem 33 that registration of the handle with the indicia indicates the position of the valve 31.

An outlet opening 36 is provided in the valve body 29 and a groove 37 in the periphery of the valve member 31 is aligned therewith. The groove 37 is of gradually increasing depth and is so positioned that when the handle 35 is aligned with the word "Off" on the panel P it is entirely out of communication with the outlet opening 36. An axial bore 38 extends into the valve 31 from the inner end thereof to a point beyond the groove 37 and a transverse bore 39 in the valve establishes communication between the groove 37 and the bore 38. When the handle 35 is moved in the direction of the arrow on the panel P, successively deeper portions of the groove 37 are brought into communication with the outlet opening 36 with the result that increasingly greater quantities of gas may flow from the outlet of the valve 23 through the bores 38 and 39 and groove 37 to the outlet opening 36. A valve of this kind enables close control of the flow of gas to the outlet opening 36 and affords very close control of the administration 40 of the gas.

A tube 40 leads from the outlet opening 36 to a suitable fitting 41 joined to a body 46 mounted in the block 6 and extending transversely thereacross above the body 10. The body 42, like the body 10, includes a plate 43 that is mounted in a countersunk recess in the outer face of the block 6. The body 42 is enlarged near the plate 43 and provides a clamp socket 44. Communication is established between the socket 44 and the fitting 41 through a bore 45 in the body 42.

A suitable pressure indicating device such as a manometer M is mounted on the panel P and suitable indicia is provided on the panel in association with the displayed indicating part of the manometer. A tube 46 establishes communication between the manometer and the fitting 41 so that pressure in the tube 40, fitting 41 and bore 45 may be indicated.

A fitting 47 is adapted to be seated in the socket 44 and a tube 48 or the like is connected to this fitting. A fitting 49 or other suitable device is provided at the free end of the tube 48. A needle is adapted to be attached to the fitting 49 when the device is used for subcutaneous injections or a suitable nozzle can be attached to this fitting when the device is to be used for rectal or nasal administration or the like.

The gauge 21 is so calibrated that it indicates the quantity of gas stored in the device and this is attained by providing the coil 20 which serves as a compensating chamber. This coil is so sized relatively to its capacity and the capacity of the other parts in the high pressure side of the device that when a predetermined pressure

is registered on the gauge 21 a predetermined quantity of gas will be stored in the high pressure side of the device, the compensating chamber in effect affording a calibration so that for each given gas pressure a predetermined quantity of gas stored in the device will be indicated on the gauge 21.

When the device is not in use the cylinders 1 are stored in the sockets S and the fitting 47 is disconnected from the socket 44, and this fitting together with the tube 48 and the fitting 49 are stored in a compartment conveniently provided in the casing C. The needles, nozzles and the like to be used with the fitting 49 may also be stored in the casing C, if so desired.

In the use of the device, it is first determined how much gas it is desirable to administer and then the boss 8 of one of the containers 1 is fitted into the tapped part 13 of the bore 12 and gas is caused to flow from the container into the coil 20, pressure reducing valve 23 and associated parts in the high pressure side of the device. The quantity of gas admitted is indicated on the gauge 21 and when the desired quantity of gas has been admitted the container 1 is backed up so as to disengage the valve stem 9 from the stud 14 whereupon the valve associated with the stem 9 and the valve 17 close, the valve 17 preventing escape of gas from the device through the tapped part 13 of the bore 12. The container 1 may at this time be disconnected and returned to one of the sockets S or it may remain fitted in the tapped part 13 of the bore 12 so as to be ready for use if and when another charge of gas is to be introduced into the device.

The fitting 47 is then seated in the socket 44 and a needle or nozzle is attached to the fitting 49. In a subcutaneous administration a needle attached to the fitting 49 is inserted under the skin of the patient and then the handle 35 is rotated whereupon gas at low pressure flows to the fitting 49. The back pressure, that is to say, the pressure at which the gas is being administered, is indicated on the manometer M and the operator will observe the pressure so indicated and by manipulating the handle 35 will regulate the flow of gas so that it will not be administered at an excessively high rate or pressure.

It will be apparent from the foregoing description that I have provided a compact device in which all of the necessary devices including a supply of gas are conveniently arranged to be transported easily. Compactness is attained by the advantageous arrangement of parts such as, for example, the nesting of the compensating coil about the pressure reducing valve and the mounting of the flow control valve on the pressure reducing valve. These features contribute to sturdiness in the device as well as to compactness.

Furthermore, the storage and compensating coil enables the gauge communicating with the high pressure side of the system to be calibrated in such a manner that the quantity of gas in the device is indicated, thereby enabling the operator to determine directly the quantity of gas available which enables a definite quantity of gas to be administered. Since the gas containers are of such a size that they may be gripped in the hand it is apparent that the flow of gas therefrom may be accurately controlled for a device so sized may be rotated easily and such movement controls flow therefrom.

Inasmuch as the gas may be directly administered to the patient it is not necessary to use an

enclosure such as an oxygen tent or the like and inasmuch as only so much gas as will be used is withdrawn from the supply and since escape of this gas is prevented it is apparent that the 5 quantity of gas consumed for a given result is relatively small and this renders the device economical to use. By reason of the accurate and close control of flow afforded by the outlet control valve and the indication of the pressure of 10 administration, the likelihood of improper use is reduced to a minimum as is the likelihood of injury to the patient.

While I have illustrated and described a preferred embodiment of my invention it is to be 15 understood that it is capable of variation and modification and I therefore do not wish to be limited to the precise details set forth but desire to avail myself of such changes and alterations as fall within the purview of the following claims.

20 I claim:

1. A physio-therapeutic device for the administration of oxygen, carbon dioxide or similar gases and having a pressure reducing valve therein, means communicating with the low pressure 25 side of said valve and including a fitting to which a gas administering needle, nozzle or the like may be connected, and other means communicating with the high pressure side of said valve and including means to which a source of gas may be 30 connected whereby a charge of gas may be admitted into said other means, said other means also including a pressure gauge and storage and compensating means, the storage and compensating means being sized to calibrate the gauge to 35 indicate directly the quantity of gas admitted into said other means as a charge whereby the magnitude of the charge of gas admitted into said other means is indicated on said gauge, and means for controlling the discharge of gas to the 40 needle, nozzle or the like whereby the administration of the charge of gas may be controlled.

2. A physio-therapeutic device for the administration of oxygen, carbon dioxide or similar gases and having a pressure reducing valve therein, means communicating with the low pressure 45 side of said valve and including a fitting to which a gas administering needle, nozzle or the like may be connected, and other means communicating with the high pressure side of said valve and including a member to which a source of gas may be 50 connected, said member having valve means therein for preventing escape from said other means through said member of a charge of gas admitted into said other means from said source 55 past said valve means, said other means also including a pressure gauge and storage and compensating means, the storage and compensating means being sized to calibrate the gauge to indicate directly the quantity of gas admitted into 60 said other means as a charge whereby the magnitude of the charge of gas admitted into said other means is indicated on said gauge, and means for controlling the discharge of gas to the needle, nozzle or the like whereby the administration 65 of the charge of gas may be controlled.

3. A physio-therapeutic device for the administration of oxygen, carbon dioxide or similar gases and having a pressure reducing valve therein, means communicating with the low pressure 70 side of said valve and including a fitting to which a gas administering needle, nozzle or the like may be connected, and other means communicating with the high pressure side of said valve and including a member to which storage means having 75 valve means therein may be movably con-

nected, said storage means affording a source of gas, valve means in said member, the valve means in said storage means and said member being operable upon movement of said storage means and said member in one direction to admit gas 5 from the storage means into said other means and being operable upon movement of said storage means and said member in the opposite direction to close off flow of gas from said storage means and through said member from said other 10 means, said other means also including a pressure gauge and storage and compensating means, the storage and compensating means being sized to calibrate the gauge to indicate directly the 15 quantity of gas admitted into said other means as a charge whereby the magnitude of the charge of gas admitted into said other means is indicated on said gauge, and means for controlling the discharge of gas to the needle, nozzle or the like whereby the administration of the charge 20 of gas may be controlled.

4. A physio-therapeutic device for the administration of oxygen, carbon dioxide or similar gases and having a pressure reducing valve therein, interconnecting means communicating with 25 the low pressure side of said valve and including a fitting to which a gas administering needle, nozzle or the like may be connected, and other means communicating with the high pressure side of said valve and including means to which a source of gas may be connected whereby a charge of gas may be admitted into said other means, said other means also including a pressure gauge and storage and compensating means, the storage and compensating means being sized 30 to calibrate the gauge to indicate directly the quantity of gas admitted into said other means as a charge whereby the magnitude of the charge of gas admitted into said other means is indicated on said gauge, means in the interconnecting 35 means for controlling the discharge of gas to the needle, nozzle or the like whereby the administration of the charge of gas may be controlled 40 thereby, and other means in the interconnecting means for indicating the pressure at which the 45 gas is administered.

5. A physio-therapeutic device for the administration of oxygen, carbon dioxide or similar gases and having a pressure reducing valve therein, interconnecting means communicating with 50 the low pressure side of said valve and including a fitting to which a gas administering needle, nozzle or the like may be connected, and other means communicating with the high pressure side of said valve and including a member to 55 which storage means having valve means therein may be movably connected, said storage means affording a source of gas, valve means in said member, the valve means in said storage means and said member being operable upon movement 60 of said storage means and said member in one direction to admit gas from the storage means into said other means and being operable upon movement of said storage means and said member in the opposite direction to close off flow of gas 65 from said storage means and through said member from said other means, said other means also including a pressure gauge and storage and compensating means, the storage and compensating means being sized to calibrate the gauge 70 to indicate directly the quantity of gas admitted into said other means as a charge whereby the magnitude of the charge of gas admitted into said other means is indicated on said gauge, means in the interconnecting means for control- 75

ling the discharge of gas to the needle, nozzle or the like whereby the administration of the charge of gas may be controlled thereby, and other means in the interconnecting means for 5 indicating the pressure at which the gas is administered.

6. A portable physio-therapeutic device for the administration of oxygen, carbon dioxide or similar gases and comprising a casing, a pressure 10 reducing valve in said casing, means in said casing communicating with the low pressure side of said valve and including a fitting opening exteriorly of said casing and to which a gas administering needle, nozzle or the like may be connected, and other means in said casing 15 communicating with the high pressure side of said valve and including means opening exteriorly of said casing and to which a source of gas may be connected whereby a charge of gas may be admitted into said other means, said other means also including a pressure gauge and storage and compensating means, the storage and compensating means being sized to calibrate the gauge 20 to indicate directly the quantity of gas admitted into said other means as a charge whereby the magnitude of a charge of gas admitted into said other means is indicated on said gauge, and means positioned exteriorly of said casing for 25 controlling the discharge of gas to the needle, nozzle or the like whereby the administration of the charge of gas may be controlled thereby.

7. A portable physio-therapeutic device for the administration of oxygen, carbon dioxide or similar gases and comprising a casing, a pressure 30 reducing valve in said casing, interconnecting means in said casing communicating with the low pressure side of said valve and including a fitting opening exteriorly of said casing and to which a gas administering needle, nozzle or the 35 like may be connected, and other means in said casing communicating with the high pressure side of said valve, a member opening exteriorly of said casing to which storage means having valve means therein may be movably connected, 40 said storage means affording a source of gas, valve means in said member, the valve means in said storage means and said member being operable upon movement of said storage means in said member in one direction to admit gas 45 from the storage means into said other means and being operable upon movement of said storage means in said member in the opposite direction to close off flow of gas from said storage means and through said member from said other 50 means, said other means also including a pressure gauge and storage and compensating means, the storage and compensating means being sized to calibrate the gauge to indicate directly the 55 quantity of gas admitted into said other means as a charge whereby the magnitude of a charge of gas admitted into said other means is indicated on said gauge, means positioned exteriorly of said casing and in the interconnecting means for 60 controlling the discharge of gas to the needle, nozzle or the like whereby the administration of gas may be controlled thereby, and other means in the interconnecting means and positioned exteriorly of the casing for indicating the pressure 65 at which the gas is administered.

8. A physio-therapeutic device for the administration of oxygen, carbon dioxide or similar gas and including a base, a panel secured to said base, a pressure reducing valve mounted on said base, a gauge mounted on said panel, means interconnecting the high pressure side of said valve and said gauge, a block secured to said panel, a member mounted in said block and to which a source of gas may be connected and communicating with the high pressure side of said valve and with 10 said gauge and having means for unseating a valve in the source of gas to effect flow of gas to said valve, compensating means associated with said valve and gauge whereby said gauge may be calibrated to indicate the quantity of gas admitted into said device through said chamber, a flow control valve mounted on said pressure reducing valve and communicating with the low pressure side of said pressure reducing valve, an operating handle for said flow control valve and 15 positioned in front of said panel, a socket mounted in said block and communicating with the outlet of said flow control valve and in which means including a fitting to which a needle or nozzle may be attached may be removably seated, 20 said flow control valve regulating flow to said socket and fitting, and means on said panel communicating with said socket for indicating the pressure of gas flowing to said socket and fitting.

9. A physio-therapeutic device for the administration of oxygen, carbon dioxide or similar gas and including a base, a panel secured to said base, a pressure reducing valve mounted on said base, a gauge mounted on said panel, means interconnecting the high pressure side of said valve 25 and said gauge, a block mounted on said base and secured to said panel, a member mounted in said block and communicating with the high pressure side of said valve and with said gauge, means in said member for detachably connecting a source 30 of gas thereto, other means in said member for unseating a valve in a source of gas attached to said member to effect flow of gas through said member to the high pressure side of said pressure reducing valve, a check valve in said member 35 adapted to be unseated by gas flowing to the high pressure side of said pressure reducing valve and adapted to seat to prevent escape of gas from said high pressure side when the means unseating the valve in the source of gas is rendered inoperative, a compensating coil associated with said pressure reducing valve and the gauge whereby said gauge may be calibrated to indicate the 40 quantity of gas admitted into said device through said member, a flow control valve mounted on said pressure reducing valve and including a part extending through an opening in said panel to which an operating handle may be connected, a socket mounted in said block and communicating with the outlet of said flow control valve and in which means including a fitting to which a needle or nozzle may be attached may be removably seated, said flow control valve including means for closing off flow to said socket and fitting and for gradually increasing the flow 45 of gas to said socket and fitting, and means mounted on said panel and communicating with said socket for indicating the pressure of gas flowing to said socket and fitting.
